UNITED STATES PATENT OFFICE.

ASHBY PERSINGER, OF SPRINGFIELD, OHIO.

WRENCH.

Application filed January 20, 1922. Serial No. 530,632.

To all whom it may concern:

Be it known that I, ASHBY PERSINGER, a citizen of the United States, residing at Springfield, in the county of Clark and State of Ohio, have invented certain new and useful Improvements in Wrenches, of which the following is a specification.

This invention relates to new and useful improvements in wrenches and more particularly to the quick adjustable type.

An important object of the invention is to provide a wrench having a movable jaw in which is incorporated a movable locking element adapted for cooperation with the rack teeth of the stationary jaw, said locking element being so mounted as to only necessitate a slight movement in order to effect adjustments of the wrench.

Another important object of the invention is to provide a wrench of this character which consists of the minimum number of parts and includes simple and inexpensive means for concealing the locking element and protecting the same from grit and other foreign matter which might otherwise gain access thereto.

Other objects and advantages of the invention will become apparent during the course of the following description.

In the accompanying drawings forming a part of the application and wherein like numerals are employed to designate like parts throughout the several views,

Figure 1 is a side elevation of the invention.

Figure 2 is a section through the movable jaw of the wrench.

Figure 3 is a transverse section of the wrench taken on the line 3—3 of Figure 2.

Figure 4 is a vertical section through the same at right angles to the section 3—3 on the lines 4—4 of Figure 2.

Referring now more particularly to the drawings wherein for the purpose of illustration is shown the preferred embodiments of my invention, the numeral 5 designates the handle and shank of the wrench, the inner edge of which is equipped with a plurality of rack teeth 6. One end of the shank 50 is equipped with a stationary jaw 7 in the well known manner.

The movable jaw of the wrench is designated by the numeral 8 and consists of a casting having an opening 9 therethrough whereby the movable jaw is slidably mounted upon the shank 5. The movable

jaw is also provided with a cut out portion 10 extending from the opening 9 through an end wall of the jaw and which is arranged at right angles to the opening 9 and 60 communicates at its inner end therewith. The top and bottom of the recess formed by the cut out portion 10 is each equipped with a longitudinally extended recess 11 which extends at right angles to the opening 9.

A locking element or block 12 has its top and bottom each provided with an outwardly extending rib 13, which ribs are adapted for sliding association with the 70 grooves 11 in the stationary jaw. The inner edge of the locking elements is equipped with a plurality of rack teeth adapted for cooperation with those of the shank 5. This locking element is prevented from displacement from the cut out portion 10 by means of a U-shaped plate 14, the arms of which are adapted to snugly fit against opposite sides of the stationary jaw and be riveted thereto by means of rivets 15. The 80 bridging portion of this U-shaped plate is adapted to fit snugly against the outer end of the recess formed by the cut out portion in the movable jaw as clearly seen in Figures 2 and 3. Each of these arms is provided 85 with an elongated slot 16 and these slots are adapted for the reception of pins 17 extending laterally from opposite sides of the locking element 12. In order that the locking element be normally retained in cooperation with the rack teeth of the shank, a coiled spring 18 is interposed between the locking element and the arched portion of the U-shaped plate 14, it being retained in its proper position by one end thereof fitting 90 in a recess in the end of a locking element. As seen in Fig. 3 the sides of the locking element are spaced from the arms of the U-shaped plate and are retained in such relationship by reason of the ribs 13 of the 100 locking element co-operating with the grooves 11 in the top and bottom of the cut out portion 10. Due to this arrangement it will be seen that quite a bit of friction will be eliminated since the sides of the locking 105 element are not permitted to rub against the arms of the U-shaped plate.

In operation, when an adjustment is to be made by moving the movable jaw 8 of the wrench, the thumb and forefinger are engaged with the pins 17 of the locking element 12 which pins project slightly beyond

the exterior surfaces of the arms of the covering plate 14 so that the locking element may be moved to disengage the rack teeth 6. The movable jaw may then be 5 moved freely along the shank of the wrench to reach the desired adjustment. After this the locking element is released so that the expansion of the coiled spring 18 forces it inwardly into engagement with the rack 10 teeth of the shank to lock the movable jaw in position.

The foregoing description and accompanying drawings have reference to what might be considered to be the approved or 15 preferred form of my invention. I desire it to be understood that I may make such changes in the construction, combination and arrangement of parts material, dimensions, etc., as may prove expedient and fall 20 within the scope of the appended claim.

Having thus fully described my invention what I claim as new and desire to secure by Letters Patent is:

A quick adjustable wrench comprising a 25 shank having a stationary jaw and rack teeth along one edge thereof, a movable jaw

having an opening therethrough for sliding engagement with said shank, said movable jaw being provided with a cut out portion extending from the opening therein through 30 the exterior-wall thereof, a locking element mounted in said cut out portion and having means for co-operation with the rack teeth of the shank, a U-shaped covering plate for the cut out portion having its arms securely 35 fastened to opposite faces of the movable jaw and its bridging portion spanning the outer open end of said cut out portion, a spring disposed between the locking element and the bridging portion of the covering plate and abutting said bridging portion to normally urge the locking element toward the rack teeth of the shank, and means extending from the locking element whereby the same can be operated exteriorly 40 of the movable jaw.

In testimony whereof I affix my signature in presence of two witnesses.

ASHBY PERSINGER.
